GARMENT DISPLAY DEVICE

Bernard R. Sieve, Chicago, Ill.

Application May 18, 1940, Serial No. 335,972

3 Claims. (Cl. 223—68)

The present invention relates generally to display forms, and in particular to forms for displaying ladies' garments such as dresses, coats, suits, swimming suits and the like.

Various sorts of mannequins, dummies, and forms, are in use for dress shops and windows, and these are somewhat expensive to warrant use of numerous ones at a single location. In substitution, there is a standard, comprising a base, a spindle support, and an arcuate hanger at the top of the spindle simulating the position of the shoulders. On this hanger is mounted a dress or coat, with the result that the dress hangs "flat" rather than in rounded normal shape as on a clothes dummy. Dress shops carry a greater number of such standards than of dummies and forms.

The present invention aims to provide an improved form constructed for support by a standard of the type referred to, whereby a mounted form is available at less cost, and whereby a standard in stock may be used in its normal way or converted into a complete display form.

Another object of the invention is to provide a form with openings in the back for the insertion of such a standard, and also useful for tucking in dress materials, where the form is used to display materials rather than sewed goods, by draping material from a bolt over the form.

Another object of the invention is the provision of an inexpensive light-weight form easy to manufacture, and highly useful in numerous ways in a display shop or window.

Various other and ancillary objects and advantages of the invention will appear from the following description and explanation of the invention, as represented by the accompanying drawing, in which:

Fig. 1 represents in perspective a form.

Fig. 2 represents a standard type of dress hanger for display.

Fig. 3 represents the combination of the form of Fig. 1 and the stand of Fig. 2, with the form in rear view.

Fig. 4 is a modified form (rear view), especially adaptable for the display of bathing suits and like legged articles.

Fig. 5 shows a modified stand of Fig. 2 as it is adapted for and used with the modified form of Fig. 4.

Fig. 6 is a view of the bottom of the form as taken on line 6—6 of Fig. 3.

Fig. 7 is a detailed view of the top of the stand.

In Fig. 1, the form may be considered as a hollow article with a shell-like structure to make

it light in weight, papier mâché being preferred. The numerals designate parts later referred to. 10 represents the form generally. 11 designates the hips, 12 the waistline, 13 the bust region, 14 the arms, 15 the shoulders, and 16 the neck, which may, if desired, support a head (not shown). As illustrated, the terminal faces of the neck and arms are preferably closed, as part of the shell. The terminal part of the hips, or base is open in whole or in part, at least to an extent to receive a standard.

In Fig. 2, a base 20 carries a tubular standard 21 in which telescopes a rod 22, held in adjusted position by thumb screw 23. The rod 22 has a threaded end 24 (Fig. 7) above a shoulder 25. An arcuate hanger 26 has a hole, which may be threaded, to fit over the threaded part 24, and to lie on the shoulder. An ornamental nut 27 then caps the threaded end 24. The arcuate hanger represents generally the curves and length of shoulders for hanging dresses thereon. The parts form a generally T-shaped hanger, and a more perfect T-shaped hanger may be used as well, as will appear naturally.

25 The rear of the form has an opening 30 across the back near the shoulder line of sufficient size to receive the hanger, or the cross arm of the T, on the interior for hanging the form by the inside under the shoulders, as on the hanger 26.

30 The opening may be extended at 31 down the spine region to the bottom edge, making wing-like portions 32 and 33 at the rear. The standard 21 may enter into this opening 31 in hanging the form 10 on hanger 26. To keep the form from rocking where it is entirely open at the base, suitable supporting means may connect the standard 21 with the body of form 10. This is illustrated by a closure member, such as a sheet of plywood 34 (Fig. 6) secured to the base. The board is preferably made in contour to conform to the opening of the base, and provides rigid reinforcement to prevent the wings 32 and 33 moving from normal designed position. The board 34 has a notch or recess 35 extending from the spinal opening 31 to a position near the center to receive the standard 21.

Dresses, coats and the like may be hung on the combination as shown in Fig. 3. Also, fabrics in the bolt, or in lengths may be draped over the form in various ways and the openings 30 and 31 and also the hanger parts may be used to receive or hold the ends, folds or loops of the fabric as is convenient for the character of the draping. Of course, it is to be understood that for some displays a shorter form may be used.

omitting the hip region 11, and even the waist-line, preserving the bust region, however, to give fullness to the display.

For displaying an article such as bathing trunks, the form of Fig. 1 is not satisfactory to give fullness to display of the trunks. By a modification, the form may be extended to provide a new form 39 with leg portions 40 (Figs. 4 and 5) extending to a point below the crotch 41, and by omitting all or part of the opening 31 in the back. The opening 30 is retained for receipt of the hanger 26 or the like. A lateral S-shaped extension 42 with a threaded socket end 43 is screwed onto bolt 24 to lie on shoulder 25 on the stand. The other end of the extension has a construction like the end of rod 22 to carry the hanger 26 or other T-cross-member, in a position forward of the spindle. The light weight of the form, the spread of the base 20, and the length of the extension, taken in consideration with the weight of garments to be displayed, are such as to prevent over-balancing of the display unit when mounted.

The opening across the shoulders and the opening of the spine are in effect and function one opening each extending the other. It is of course to be understood that the general shape of this opening may be varied from the T-form of Fig. 3 and from the line-form of Fig. 4, and also varied in shape. The length of the shoulder opening may be shortened where a shorter support than the standard hanger 26 is used.

Numerous changes and modifications of the device are contemplated in the appended claims.

I claim:

1. A form of the human figure for the display of wearing apparel comprising a shell-like structure in a shape of the torso including at least the shoulders, back and bust region, the shell being open at the base and open from the bottom of the

base upwardly along the region corresponding to the spine to a region in the vicinity of the shoulder line, and being open on the back in the vicinity along said shoulder line, whereby T-shaped standard may be inserted into the form for mounting the form internally at the shoulders, the form being such that when it is supported by resting of the shoulder portions on the said standard, the form depends by gravity in natural body-erect position.

2. A form of the human figure for the display of wearing apparel comprising a shell-like structure in a shape of the torso including at least the shoulders, back, bust and hip regions, the shell being open at the base and open from the bottom of the base upwardly along the region corresponding to the spine to a region in the vicinity of the shoulder line, and being open on the back in the vicinity along said shoulder line, whereby a T-shaped standard may be inserted into the form for mounting the form internally at the shoulders, the form being such that when it is supported by resting of the shoulder portions on the said standard, the form depends by gravity in natural body-erect position.

3. A form of the human figure for the display of wearing apparel comprising a shell-like structure in a shape of the torso including at least the shoulders and the back, and a T-shaped opening on the back extending to the bottom edge of the form, the bottom of the form being open sufficiently to permit the insertion of a T-shaped standard into the form for mounting it by the shoulders on the interior thereof, the form being such that when it is supported by resting of the shoulder portions on the said standard, the form depends by gravity in natural body-erect position.

BERNARD R. SIEVE.
